TRACTOR OPERATED LOG AND TREE SAW

August F. Pfingsten, Rock Rapids, Iowa

Application June 18, 1945, Serial No. 600,026

1 Claim. (Cl. 143—19)

1

My invention relates to a log and tree saw.

An object of my invention is to provide a saw which can be operated from a tractor power take-off shaft.

A further object of my invention is to provide a saw which includes all of the advantages of a band saw in that it travels at a rapid speed, is not reciprocating in action, and can be placed in practically any desired position.

A further object of my invention is to provide a tractor operated saw which will be driven during any angular movement thereof.

A further object of my invention is to provide an arrangement which is easily controlled by the operator, and can be adapted to various log diameters.

A further object of my invention is to provide a saw of this character which can be readily adapted for sawing down trees by merely adding a simple attachment thereto.

A further object of my invention is to provide a saw of this nature which is simple in construction and which can be manufactured at a reasonable cost.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a side elevation of the saw during use thereof.

Figure 2 is a plan view of Figure 1 showing the saw in substantially horizontal position.

Figure 3 is a sectional detail taken along the lines 3—3 of Figure 2.

Figure 4 is a sectional view of Figure 2 taken along the lines 4—4 thereof.

Figure 5 is an elevation showing the saw when used for the tree cutting operation, and

Figure 6 is a plan view of Figure 5.

I have used the character 10 to designate a tractor draw-bar, the character 11 the tractor rear housing, and the character 12 the rear tractor power take-off shaft. Firmly attached to the shaft 12 is a socket 13 which is attached by means of the screws 14, and attached to the socket 13 is a universal joint 15 to which is attached at 16, a hollow square shaft 17 in which is received a solid square male shaft 18. The shaft 18 is attached at 19 to a universal joint 20 (see Figure 3) and the joint 20 is adapted to drive the shaft 21 which is suitably journaled at 22 within the hollow casing 23. A protecting hous-

2

ing 24 which is a continuation of the casing 23, encloses the joint 20.

Attached at the end of the shaft 21 is a vertical bevel gear 25 which meshes with a horizontal bevel gear 26 to which is attached a shaft 27 which is journaled at 28 within the top 29 of the casing 23. Attached to the gear 26 is a square member 30 which is engaged within a square portion 31 of a socket 32 which is attached to the upper portion 33 of a clutch member having the lower portion 34, the portions 33 and 34 including the serrated, snugly engaged portions 35. Attached to the lower clutch portion 34 is a shaft 36 which is attached at 37 to a substantially large pulley 38 which includes a rubber or other facing 39 about which facing is snugly engaged a continuous band saw 40 having the teeth 41. Enclosing the pulley 38 is a casing 42 having a small projection at 43 and having an opening at 44 through which opening the band saw passes.

The lid 29 is attached at 45 to a transverse strap 46 which is attached at 47 to a pair of spaced arched members 48. The members 48 terminate in the end portions 49 which extend into the transverse members 50. A further brace 51 which is attached at 52 to the members 48, is attached at 53 (see Figure 4) to a further housing 54 in which is received a collar 55 to which is attached a shaft 56 which shaft is attached at 57 to a further pulley 58 having the rubber or other facing 59, the continuous band saw 40 also passing about this pulley. A further housing 60 which includes the small projections 61 encloses the pulley 58. A pair of handles 62 are attached at 63 to the arched members 48.

It will be noted from Figure 2 that the members 48 are spaced apart a sufficient distance so that they extend slightly beyond the traveling band 40 at either side.

Attached to the lower left hand corners of the frame-work at 64 are a pair of eye-bolts 65.

For sawing fallen logs, the arrangement is used in the following manner, and as shown in Figures 1 and 2. The left hand side of the framework, or the side bearing the gears, etc., is rested upon the ground, and the tractor engine is started. The framework is supported by means of the handles 62 and at an angle above the log with provision being made for one side of the band 40 to clear the end 66 of the log (see Figure 2). The spacing between the bands is made sufficient to allow for the greatest length of log section, so that shorter lengths can be cut if desired. The arrangement is then pivoted downwardly in the direction of the arrow 67 until the log is cut

completely through and when the arrangement is then in the horizontal position. The curved frames 48 permit the arrangement to accommodate maximum log diameters.

It will be noted that the drive is applied to the shafts 17 and 18 and thence through the bevel gears 25 and 26 to the pulley 38. The clutch surfaces at 35 permit the upper clutch portion 33 to side freely when the band saw sticks due to the pressure against the compression spring 68 which allows the socket 32 to rise. The slight projections 43 and 61 retain the band saw against slipping out of the casing as well as the openings 44. It will also be noted that the saw can be positioned at any point away from the tractor, can be moved side-ways, or downward without affecting the operation while the power is applied due to the slideable movement permitted between the shafts 17 and 18 and due to the universal joints 15 and 20.

If desired, the log, which is indicated by the character 69, can be set up on blocks to insure that the band saw will saw completely through the lower edge, although normally the bark on the log may not necessitate the same.

Figures 5 and 6 illustrate how the arrangement is used for sawing down trees in which figures the tree is indicated by the character 70. In this arrangement a special bracket 71 is bolted at 72 to the tractor draw bar 10, and the bracket 71 includes the horizontal portion 73 which includes the square socket 74 therein in which is received the rod 75, the lock nuts 76 serving to lock the log 75 in any selected position, thereby allowing longitudinal movement of the rod 75. The bolt 72 permits angular movement of the bracket so that the position of the saw can be adjusted to meet any requirements. The rod 75 includes a shoulder at 77 to which is attached the vertically extending circular rod 78.

In use the eye bolts 65 are slipped over the vertical rod 78 which turns the saw arrangement on its side as shown in Figure 5; and the rod 78 thereby provides a pivoting point for the entire frame, so that the frame can then be swung in the direction of the arrow 79 (see Figure 6) with the band 40 then cutting through the tree. In this instance, both bands will necessarily cut through the vertical tree, the linear speed thereof permitting a smooth cutting action. Attached to the bracket portion 73 at 80 is a vertical brace 81 which rests upon the ground to steady the entire arrangement. It will be noted that the power is still applied in the same manner as described heretofore in this latter use. A flexible shaft arrangement can be employed, one end of which would be attached to the take-off shaft 12, and the other end to the small shaft 21, although the above described arrangement may be the preferred form.

It will now be seen that I have provided a log and tree saw including all of the advantages mentioned in the objects of my invention with further advantages being readily apparent.

Some changes may be made in the construction and arrangement of the parts of my invention without departing from the real spirit and purpose of my invention, and it is my intention to cover by my claim any modified forms of structure or use of mechanical equivalents which may be reasonably included within their scope.

I claim as my invention:

A tractor operated saw comprising an arcuate frame-work for receiving a log therein, said frame-work including a pair of rotatable pulleys journaled one at each end thereof, a band saw engaged with said pulleys, means for driving one of said pulleys from a tractor power take-off shaft, including a drive shaft connected to said power take-off shaft, said drive shaft including mutually attached sections permitting longitudinal movement of the drive shaft, said drive shaft including universal joints at the terminals thereof for permitting desired pivotal movement of the saw, a casing positioned above one of said pulleys, a bevel gear attached at a terminal of said drive shaft, a further beveled gear meshing with said bevel gear, one of said band saw pulleys being driven by said further bevel gear, a clutch member interposed between said further bevel gear and said pulley, said frame including a part of arcuate supports, handles attached to said supports for guiding said saw, means for cutting trees with said saw including a bracket member attached to the tractor draw bar, an extensible vertical rod attached to said bracket, a pair of eye-bolts attached to the saw frame for receiving said vertical rod, whereby said saw will be positioned on its side to cut through a vertical tree.

AUGUST F. PFINGSTEN.
